Inventor;

Louis J. Parsons

LOUIS J. PARSONS, OF NEW BEDFORD, MASSACHUSETTS.

Letters Patent No. 83,205, dated October 20, 1868.

IMPROVED MODE OF FASTENING APRON-HOOKS TO THE DASHER-FALLS OF CARRIAGES.

The Schedule referred to in these Letters Patent and making part of the same.

To all whom it may concern:

Be it known that I, LOUIS J. PARSONS, of New Bedford, in the county of Bristol, and State of Massachusetts, have invented a new and improved Mode of Fastening "Apron-Hooks" to the "Dasher-Falls" of Carriages; and I do hereby declare that the following is a full and exact description thereof, reference being had to the accompanying drawings, and to the letters of reference marked thereon.

My invention consists in a metallic clasp, bent in such manner as to form a loop for reception of eye of "apron-hook," and provided with lips upon the back side, by which to secure the clasp to the "fall."

Figure 1 is a perspective view of a portion of a "dasher-fall" to which is secured an "apron-hook" by my invention.

Figure 2 is a back view of clasp, showing the lips by which it is secured to the "fall."

Figure 3 is a back view of a portion of a "dasher-fall" having my invention attached, showing the lips bent over, to secure the clasp.

Fig. 1, A¹ is a portion of a "dasher-fall."
B¹ is the clasp.

Fig. 2. B², clasp.

a² a² a², lips on back side of clasp.

Fig. 3. A³, portion of "fall."

a³ a³ a³, lips of clasp pressed through the "fall," and turned down to secure the clasp to the "fall."

The dotted lines show the form of clasp and eye of hook.

In applying this clasp, slits will be cut in the "fall" corresponding to the lips a² a² a², which lips will then be passed through and clinched.

By using this invention, much time will be saved, the expense will be less, and the hook more strongly secured, and neater in appearance.

Claim.

What I claim as my invention, and desire to secure by Letters Patent, is—

Securing hooks or rings to "dasher-falls" by metallic clasp B², substantially in the manner described.

LOUIS J. PARSONS.
